(57) CLAIM

The ornamental design for the golf putting training device, as shown and described.

DESCRIPTION

FIG. 1 is a perspective view of the present invention with the golf putting training device superposed an exemplary golf green; and

FIG. 2 is a front view of the present invention; and

FIG. 3 is a rear view of the present invention; and

FIG. 4 is a left side view of the present invention; and

FIG. 5 is a right side view of the present invention; and,

FIG. 6 is a top view of the present invention.

Wherein the dotted lines herein illustrate environment and use and do not form any part of the claimed design.

1 Claim, 4 Drawing Sheets

FIG. 1

FIG. 2

FIG. 3

FIG. 4

FIG. 6
